STOP MOTION DEVICE FOR KNITTING MACHINES

Vladimír Hanzl and Hynek Lunák, Trebic, Czechoslovakia, assignors to Zapadomoravské Strojirny, národní podnik, Trebic, Czechoslovakia

Application September 6, 1957, Serial No. 682,339

Claims priority, application Czechoslovakia
September 7, 1956

5 Claims. (Cl. 66—157)

The present invention relates to a stop motion device for knitting machines, more particularly for circular knitting machines for the manufacture of seamless tubular goods, which machines are provided with mechanisms for both guarding and opening the needle latches, as well as for thread guarding and with mechanisms acting on the drive of the machine to halt operation of the latter in the event of any trouble occurring in the latches and butts or breaking or running out of the thread.

One of the recently developed known stop motion devices for knitting machines employs a plurality of mechanical stop motions which, in the event of a breakdown of the needle latches or butts, brings about a deflection of the respective feeler or pusher, and each of the stop motions acts individually on a mechanical central organ controlling the stop motion mechanism included in the belt pulleys of the machine to effect disengagement from the primary drive shaft and consequently stoppage of the machine.

A disadvantage of this well known device consists in that the stoppage of the machine is not instantaneous owing to the inertia of the stop motion mechanism mounted in the belt pulleys. A further disadvantage lies in the fact that the disengagement from the primary drive shaft is not reliable, owing to the intricacy of the mechanism provided therefor which is susceptible to frequent breakdowns, and moreover re-engagement with the primary drive shaft is effected by hand and requires a certain amount of skill on the part of the attendant.

It is an object of the present invention to eliminate the above disadvantages of the hitherto known devices, by providing a simpler and more convenient design having individual stop motions and a central disengaging organ which cooperate to safeguard the reliable operation of the machine and which, in case of a needle or yarn defect, bring the knitting machine to a stop in a quarter of a revolution of the machine.

The main feature of a stop motion device embodying the present invention consists in the use of a plurality of electric guard elements acting individually on a central stop motion organ which, through electromagnetic means, directly controls the drive, for example, the electric motor, of the whole machine.

The above, and other objects, features and advantages of the present invention will be evident from the following detailed description of an embodiment thereof given by way of example and illustrated in the accompanying drawings, wherein:

Fig. 1 is a front elevational view of the general arrangement of the individual electric guard elements, the central stop motion organ and signalling device of a single-cylinder knitting machine embodying the invention,

Fig. 2 is a side elevational view of the general arrangement of the machine of Fig. 1 and showing the individual mechanisms and electric motor of the machine,

Fig. 3 is an elevational view of an electric stop motion device included in the machine of Figs. 1 and 2, but shown on an enlarged scale,

2

Fig. 4 is a plan view of the device of Fig. 3, with the top covering part removed, and on an enlarged scale,

Fig. 5 is a detail sectional view taken along the plane *a—a* of Fig. 4,

Fig. 6 is a perspective view of the electric stop motion device of the needle latches and needle latch opener as viewed in the direction of the arrow *S* on Fig. 1,

Fig. 7 is a detail sectional view showing the arrangement of the needle latch guards and taken along the plane *b—b* of Fig. 6, but on an enlarged scale,

Fig. 8 is a detail sectional view taken along the plane *c—c* of Fig. 7,

Fig. 9 is a plan view of the guard of the needle butts and of the central electric breaking device of the machine of Figs. 1 and 2, but on an enlarged scale, and

Fig. 10 is a wiring diagram of the individual stop motion devices connected to the central stop motion device and electric motor of the knitting machine.

Referring to the drawings in detail, and initially to Fig. 6 thereof, it will be seen that the electric guard device *A* of the needle latches consists of the well known feeler *1* with a widened flat end portion *2* adapted for coming into touch with released needle latches *3* within the range of the circulating needles *4*. The feeler *1* is adjustably fixed in the head *5* of the vertical and rotatable pivot *6* for lateral swinging movement, in the direction of the arrow on Fig. 6, between an active position indicated in full lines at *I* and an inactive position indicated in broken lines at *II* and a further position not illustrated in the drawing. A housing *7* carrying the pivot *6* and fixedly connected with the stop motion lever *8* is adapted for vertical adjustment in the direction of its longitudinal axis. A sleeve *9* is attached to housing *7* in an insulated manner, and has a projection forming an electric contact or terminal *11* for the current conductor *12*. A further electric contact *13* is provided on pivot *6* below sleeve *9* and has a projecting portion *14* adapted for co-operation with a projecting portion *16* of the electric contact *11*. A setting ring *16* is fixed adjustably to the lower end of pivot *6*, as by a screw, said setting ring being connected with the contact *13* through a torsional spring *17* (Fig. 7). This torsional spring *17* holds the contact *13* in such a position that a projecting portion *18* on the latter steadily bears against the screw *15*. The stop motion lever *8* which is fixedly connected with the housing *7* is supported pivotally within a fork *19* of an extension member *20* fixed adjustably in a holder *21* (Fig. 6) of the machine. The lever *8* is provided with an abutment pin *22*, against which the feeler *1* is urged by a spring *23* connected, at its ends, to the pin *22* and the feeler *1*. A spring *24* is connected between the pin *22* and extension member *20*. A pivot *25* (Fig. 7) is carried by the lever *8*, and one end of a connecting rod *26* is adjustably supported in the pivot *25*, while the other end *27* of rod *26* is widened and provided with a longitudinal slot *28*. An abutment pin *29* is guided in slot *28*, and a wire *31* is made to bear thereagainst by the action of a spring *30*. The wire *31* and a needle latch opener *32* are secured in a movable plate *33* which is supported pivotally on a pin *34* carried by an upright *35*. The abutment pin *29* is pressed into an arm *36* fixed at the top end of a vertical column *37*. The bottom end of column *37* carries a longer arm *38* with a pin *39* in which one of the ends of a connecting rod *40* is secured. The other end of rod *40* is guided in a pin *41* at the free end of a lever *42* and is secured by a setting ring *43*. The lever *42* has a nose *44* and is pivotally supported on a carrier pin *45* of the machine frame not illustrated in the drawings. A spring *46* connected between the arm *36* and the upright *35* urges the nose *44* against the surface of a well known control drum *47* of the machine.

so that the lever 42 is rocked by contact of nose 44 with a segment 48 fixed on the drum 47.

The pivot 49 connecting the well known frame of the apparatus 50 with the bracket 51 is provided with a profiled arm 52 adapted to act, at its free end 53 on the widened end 27 of the connecting rod 26.

The needle butt guard device B (Fig. 9) consists of the well known pusher member 54 supported pivotally on an eccentric pivot 55 carried by the upright 51. The free bent end 56 of the pusher member 54, when the latter is in the active position III, extends beyond the lowered needles 4 as well as the respective sinkers which are not included in the drawing. The pusher member 54 has an elastic wire 57 fixed thereto, and the free end of wire 57 carries a hammer 58 which is adapted to cooperate with a central electric interrupter device D. A connecting rod 60 is connected at one end to the pusher member 54 and is guided in a lever 59 with a spring 61 mounted on rod 60 serving, in conjunction with a lever gear (not illustrated in the drawing), for shifting the pusher member to its inactive position shown in broken lines at IV where pusher member 54 remains during the knitting of certain parts, for example, the heel and toe, of the stocking.

The electric guard device C for the heel threads (Figs. 1 and 2) includes an L-shaped stationary wire contact 62 having a longer arm fixed adjustably in an insulating ring 63 on the holder 64 of the heel drawing off device. The contact 62 is adjusted in such manner that a wire probe 65 engages a shorter arm of the contact 62 only in the case of breakage of a heel thread or if the heel yarn spool is empty. The contact 62 is sufficiently remote from the wire probe 65 so as to prevent any contact occurring during the normal operation of the machine in knitting the heel, at which time the wire probe 65 has a swinging motion imparted thereto determined by the length of the thread. The end of the longer arm of the contact 62 is connected through a current conductor 66 with the central electric interrupter device D.

The central electric interrupter device D (Fig. 4) acted upon by the individual independent guard mechanisms A, B, C consists of a plate member 67, in which two co-operating levers 70, 71 are supported pivotally on pins 68 and 69. The lever 70 has a relatively long arm 72 provided with an armature 73 and projecting beyond the plate member 67. The lever 70 has a relatively short arm 74 with a claw 75 at its free end cooperating with a claw 76 provided on an arm 77 of the lever 71. The lever 71 has another arm 78 projecting beyond the plate member 67. The mutual engagement of claws 75 and 76 is secured by two control springs 79, 80 which, at one end, are connected to a hinge 81 and, at the other ends, are connected to arm 74 of lever 70, and to a third arm of lever 71, respectively. A holder 82 is fixed to the plate member 67 at a location next to the arm 77 of lever 71 and carries a square member forming a stationary electric contact 83 (Figs. 4 and 5). An auxiliary electromagnet M (Fig. 4) is fixed to plate member 67 close to the armature 73, and acts, by way of an auxiliary relay RP (Fig. 2), on the electric motor E of the machine. A pivot 84 extending through the center of the plate member 67 and screwed into a holder 85 carries a covering bell-shaped part 86 (Fig. 3). The holder 85 is fixed adjustably on a vertical tubular member 87 of the machine provided at its top end with a signalling device F having a red lamp 88 (Figs. 1 and 2) connected with the auxiliary relay RP by way of a transformer Tr (Fig. 1).

The mechanisms described above operate in the following manner:

During the normal knitting operation, for example, during knitting of the stocking heel without any defect occurring on the needles, the stop motion device D is at rest, as shown in Fig. 4. The claws 75, 76 under the control of the springs 79, 80 are engaged so that the

armature 73 of the lever 70 is kept remote from the electromagnet M and the arm 77 of the lever 71 is held away from the electric contact 83. Thus, the low voltage circuit between the device D and the relay RP is interrupted (Fig. 10).

The feeler 1 of the organ A is urged by the spring 23 against the pin 22 of the lever 8 to occupy its active position I (Fig. 6) where the end 2 of the feeler 1 is in close proximity to the needles 4 moving in the direction indicated by the arrow, without the end 2 being influenced by the latches 3. Through the effect of the torsional spring 17 (Fig. 7) connecting the setting ring 16 with the contact 13, the projecting part 18 of contact 13 is urged towards the screw 15 of the setting ring 16, while the projecting part 14 of the contact 13 is remote from the projecting part 10 of the contact 11 (Fig. 8). The above mentioned relative positions of the projecting parts 10, 14 (Fig. 8) is determined by the position of the lever 8 (Fig. 6) connected through the rod 26 with pin 29, and, during guarding of the needle latches 3 of the needles 4 by the feeler 1, the rod 26 permits the needle latch opener 32 to remain in its inactive position V when its hook is outside the range of the needles. The opener 32 is moved to its inactive position V by the cooperation of the nose 44 of the lever 42 with the surface of drum 47.

During the operation of the machine with the frame of the apparatus 50 in a horizontal position, the arm 52 assumes the inactive position VII, wherein its free end 53 does not act upon the widened end 27 of the connecting rod 26.

The pusher member 54 of the needle butt guard device B (Fig. 9) is held in its active position III through the effect of the connecting rod 60 and thrust spring 61, while the hammer 58 of the wire 57 is remote from the arm 72 projecting beyond the bell 86 of the interrupter device D.

The position of the wire contact 62 of the heel yarn guard device C (Figs. 1 and 2) remains unaltered during knitting of the whole stocking. The circuit between the wire contact 62 and relay RP as well as the electromagnet M of the interrupter device D is open (Fig. 10), and the lamp 88 of the signalling device F does not light.

When a defect occurs at any of the needles 4 with the respective latch 3 in a lifted position IX (Fig. 6), the abutment of the latch 3 against the end 2 causes lateral deflection of the feeler 1 from its active position I into its rest position II in opposition to the action of the spring 23. Such deflection results likewise in an angular displacement of the pivot 6 and setting ring 16. The torsional spring 17 turns the contact 13 until its projecting part 14 is brought into engagement with the projecting part 10 of the contact 11. A circuit is thereby closed, as can be seen in Fig. 10, from one pole of the current source 89 through the simple switch 90-91, rest contacts 92-93 of the auxiliary relay RP to the coil 94-95 of the electromagnet M, and, by a conductor connected to the coil 96-97 of the auxiliary relay RP, to the feed transformer Tr₁. The coil 94-95 of the electromagnet M is fed with voltage from the feed transformer Tr₁ and thereby attracts the armature 73 (Fig. 4) of the longer arm 72 of the lever 70 to swing the latter about the pivot 68 so that the claw 75 is disengaged from the claw 76 of the lever 71. The released lever 71 is angularly displaced by the action of the spring 80 about the pivot 69 so that the arm 77 touches the electric contact 83. Thereby voltage is fed from transformer Tr₁ to the coil 96-97 of the relay RP and the latter attracts its armature to switch over its contacts so that the three movable contacts 92 engage the contacts 98, 99 and 100, respectively. Thus, the electric circuit for energizing the coils 101-102 of the contactors ST₁, ST₂, ST₃ is interrupted and the electric motor E of the machine is instantaneously stopped. Further, the switch, ing over of the contacts of the auxiliary relay RP into

the position 99—92 and 100—92, closes the circuit through the transformer Tr and the red lamp 88 of the signalling device F lights up. The opening of the normally closed contacts 93—92 interrupts the electric circuit to the electromagnet M so that the latter becomes inactive. The machine is re-started by pushing the arm 78 of the lever 71 of the interrupter device D in the direction towards the holder 85 (Fig. 4).

If the butt (not illustrated) of any needle is broken off, then the respective needle 4 (Fig. 9) is not drawn down by the lock (not illustrated) but continues to project above the level of the sinkers (not illustrated) and its top portion abuts against the free end 56 of the pusher member 54 which is in its active position III. Thus, the pusher member 54 is made to swing about the pivot 55 into its inactive position IV, but the member 54 is immediately returned to its active position III by the thrust spring 61. During the return of member 54 from position IV to position III, the wire 57 moves from position IV past position III to position X, by reason of the inertia of hammer 58, and, in position X, the hammer 58 strikes the arm 72 (Fig. 9) of the lever 70 (Fig. 4) of the interrupter device D. The action of hammer 58 on arm 72 causes the lever 70 to swing about the pivot 68 thus disengaging the claw 75 from the claw 76 of the lever 71. Spring 80 then brings the arm 77 of the lever 71 against the electric contact 83, thus closing the low voltage circuit operating the relay RP controlling the electric motor E. On its striking the arm 72, the hammer 58 also strikes the bell 86, thus drawing the attention of the operator to the stoppage of the machine. Re-starting of the machine is achieved by pushing the arm 78 of the lever 71 in the direction toward the holder 85.

In the event of a heel thread breaking or running out, the wire probe 65 is made to swing from position XI into position XII (Fig. 2) where it comes into contact with the contact 62. Thus the circuit is closed, as can be seen in Fig. 10, from one pole of the current source 89 over the switch 103—104, rest contacts 92—93 of relay RP to the coil 94—95 of the electromagnet M of the interrupter device D. The further effect on the circuit of the auxiliary relay RP is the same as in the above described cases involving the contacts 77 and 83.

At the start of the knitting operation, when there is no knit ware on the needles and the latches 3 of the needles can assume the released position IX (Fig. 6), the operation of the guard device A is not required, but, on the other hand, the operation of the needle latch opener 32 is indispensable. In order to enable the feeler 1 to move from its active position I into the inactive position II without being influenced by the needle latches and at the same time to enable the needle latch opener to move from its hitherto inactive position V to its active position VI, that is, in a direction into the needles, the drum 47 is displaced angularly in the direction of the arrow on Fig. 6 as to move the nose 44 of the lever 42 from the drum surface onto the segment 48. Thus the lever 42 is made to swing about the pivot 45, and, by way of the rod 40, the lower arm 38 and the column 37, to cause swinging of the upper arm 36 and pin 29 in a direction towards the feeler 1. The spring 30 maintains the contact of the wire 31 with the pin 29, so that the plate 33 with the opener 32 is likewise swung into its active position VI. The above described movement of the pin 29 is transmitted to the rod 26 which deflects the lever 8 with pin 22 against the action of the spring 24, and the pin 22 acts against feeler 1 to move the latter to its inactive position II. The relative position of the projecting parts 10, 14 (Fig. 8) of contacts 11, 13 is not changed during this action of the opener 32 and feeler 1 so that the circuit remains broken.

In order to permit the frame 50 (Fig. 6) of the apparatus to be raised and the feeler 1 to be swung into its inactive position II without moving the opener 32 to its inactive position V, for example, when changing a defective needle, the free end 53 of the arm 52 moves from its

inactive position VII into its active position VIII and, during the raising of the frame 50 and turning of the pivot 49, acts on the widened end 27 of the rod 26. The rod 26 is thus shifted towards the guard device A causing the feeler 1 to swing into its inactive position II. During the above mentioned movement of the rod 26, its longitudinal slot 28 does not affect the pin 29 so that the opener 32 remains in its inactive position V.

In addition to the guard device C above described for 10 guarding the heel yarn it is possible to provide a further guard device guarding the normal threads which, in the event of over-tension, breakage or running out of a normal thread, would act independently on the other guard devices in the same manner on the central electric interrupter device D.

The arrangement according to the present invention is chiefly intended for use on circular knitting machines with latch needles for the manufacture of seamless tubular goods, but its application is in no way limited to this kind 20 of goods and it can be utilized likewise in circular knitting machines for the manufacture of other knitware, such as, wearing apparel.

We claim:

1. In a circular knitting machine having an electric 25 drive motor and a relay circuit for controlling the operation of the latter; the combination of needle latch guard means having normally open contacts which are closed in response to a defect at a needle with the latch in released position; yarn break detecting means having normally open contacts which are closed in response to a defect in the feeding of a related yarn; needle butt guard means having a hammer normally retained in an inoperative position and being actuated to an operative position upon breaking of a needle butt; and an interruptor device 30 including a fixed contact, a pivoted contact lever, means yieldably urging said contact lever against said fixed contact, circuit means connecting said fixed contact and contact lever in said relay circuit to halt the operation of the electric drive motor upon engagement of said contact lever with said fixed contact, a pivoted latch lever engageable with said contact lever to hold the latter spaced from said fixed contact for normally permitting continued operation of the drive motor, said hammer acting mechanically 35 against said latch lever to release the latter from said contact lever upon movement of said hammer to said operative position, a normally de-energized electro-magnet disposed adjacent said latch lever, an armature on said latch lever adapted to be attracted by said electro-magnet to release said latch lever from said contact lever upon energization of said electro-magnet, and circuit 40 means for energizing said electro-magnet having said normally open contacts of the needle latch guard means and of the yarn break detecting means interposed therein to energize said electro-magnet only upon closing of any of said normally open contacts.

2. In a circular knitting machine; the combination as 45 in claim 1, wherein said contact lever and latch lever have cooperating claws which are mutually engageable to hold said contact lever spaced from said fixed contact.

3. In a circular knitting machine; the combination as in 50 claim 1, wherein said interruptor device further includes a plate member having said contact and latch levers pivotally mounted thereon, said contact lever has an arm extending beyond said plate member and by which said contact lever can be manually pivoted away from said fixed contact for re-engagement by said latch lever, and said latch lever has an arm extending beyond said plate member to be mechanically acted upon by said hammer.

4. In a circular knitting machine; the combination as 55 in claim 3, wherein said interruptor device further has a bell mounted on said plate member to be struck by said hammer when the latter acts mechanically on said projecting arm of the latch member for providing an audible signal indicating actuation of said needle butt guard means.

5. In a circular knitting machine having an electric

drive motor and a relay circuit for controlling the operation of the latter; the combination of an interruptor device including a fixed contact, a pivoted contact lever, means yieldably urging said contact lever against said fixed contact, circuit means connecting said fixed contact and contact lever in said relay circuit to halt the operation of the electric drive motor upon engagement of said contact lever with said fixed contact, a pivoted latch lever engageable with said contact lever to hold the latter spaced from said fixed contact for normally permitting continued operation of the drive motor, an armature on said latch lever, and an electro-magnet adjacent said armature and operative, when energized, to attract said armature for angularly displacing said latch lever so as to release said contact lever for engagement with said fixed contact; mechanical guard means operative, in response to a failure in a related function of the knitting machine, to act mechanically on said latch lever so as to release said con-

tact lever; electrical guard means having normally open contacts which are closed in response to a failure in a related function of the knitting machine; and circuit means for energizing said electro-magnet of the interruptor device and having said normally open contacts interposed therein so that said electro-magnet is energized to release said latch lever from said contact lever when said normally open contacts are closed.
